UNITED STATES PATENT OFFICE.

CHARLES BRISTOW AND MURDOCK McDONALD, OF BUTTE, MONTANA.

LIQUID POLISH.

1,278,843.

Specification of Letters Patent. Patented Sept. 17, 1918.

No Drawing.

Application filed November 17, 1917. Serial No. 202,556.

To all whom it may concern:

Be it known that we, CHARLES BRISTOW and MURDOCK McDONALD, citizens of the United States, residing at Butte, in the 5 county of Silver Bow and State of Montana, have invented certain new and useful Improvements in Liquid Polishes, of which the following is a specification.

This invention relates to certain improvements in liquid polishes and it is an object 10 of the invention to provide a novel and improved polish which is particularly adapted for use in connection with wood, leather or other polished surfaces and wherein our improved polish serves to substantially eliminate scratches, removes spots and also serves 15 as a preservative to the wood, leather or other material with which our polish may be employed.

It is also an object of the invention to 20 provide a novel and improved polish which leaves no grease or gummy surface and which, when applied, dries within a very short period of time.

Our polish consists of three parts of 25 neutral oil of petroleum to one part of cider vinegar. The neutral oil serves to obliterate scratches, remove spots and as a preserva-

tive to wood or leather and also results in the necessary gloss being given to the surface. While the cider vinegar facilitates the cleansing operation, it has been fully demonstrated in practice that it effectively serves as a drier. When our polish is applied to a surface said surface dries sub- 30 stantially instantaneously.

It has also been fully demonstrated in actual practice that our polish serves as a protection against the elements and which renders it of particular value in connection 35 with automobile cushions, leather tops and other accessories. In applying our polish the cloth is saturated with the admixture and after being applied the polish is rubbed with a dry cloth.

40 We claim:

A liquid polish consisting of three parts of neutral oil and one part of cider vinegar.

In testimony whereof we hereunto affix 45 our signatures in the presence of two witnesses.

CHARLES BRISTOW.
MURDOCK McDONALD.

Witnesses:

C. S. PASSMORE,
S. M. PASSMORE.
